UNITED STATES PATENT OFFICE.

WILLIAM A. WILLIAMSON, OF NEWARK, NEW JERSEY.

CAN-OPENER.

1,269,031.

Specification of Letters Patent. Patented June 11, 1918.

Application filed October 23, 1916. Serial No. 127,060.

To all whom it may concern:

Be it known that I, WILLIAM A. WILLIAMSON, a citizen of the United States, residing at Newark, in the county of Essex and State of New Jersey, have invented certain new and useful Improvements in Can-Openers; and I do hereby declare the following to be a full, clear, and exact description of the invention, such as will enable others skilled in the art to which it pertains to make and use the same, reference being had to the accompanying drawings, and to characters of reference marked thereon, which form a part of this specification.

This invention relates, generally, to improvements in can openers; and, the present invention has reference, more particularly, to a novel device in the form of a can opener which is provided with a perforating point at one end of the bar, and has slidably disposed upon said bar a novel form of cutter which is adjustable, so that the can opener may be used for cutting tops of metal packages of different sizes.

The present invention has for its principal object to provide a novel can opener of the general character hereinafter more particularly set forth, and one, in which the adjustable cutter is preferably provided with suitable spring-action so as to closely hug the longitudinal side-edges of the bar against accidental movement, but still permitting of the operator to slide the said cutter upon the bar, so that thereby any slight lateral movement independently of the radius-bar is obviated, and whereby greater efficiency in operation, as well as economy in cost of manufacture is attained.

Other objects of the present invention not at this time more particularly enumerated will be clearly obvious from the following detailed description of the present invention.

With the various objects of the invention in view, the said invention consists, primarily, in the novel can opener hereinafter set forth, as well as in the novel arrangements and combinations of the various devices and parts, and the details of the construction of the same, all of which will be more fully described in the following specification, and then finally embodied in the clauses of the claims which are appended to

and which form an essential part of the 55 said specification.

The invention is clearly illustrated in the accompanying drawings, in which:—

Figure 1 is a top-face view, and Fig. 2 a bottom-face view of a can opener showing one embodiment of the principles of the present invention.

Figs. 3 and 4 are the two side-edge views of the can opener; Fig. 5 is a transverse vertical section of the same, looking in the 65 direction of the arrow *x*, said section being taken on line 5—5 in Fig. 1; and Fig. 6 is a similar section taken upon the same line 5—5 in said Fig. 1, but looking in the direction of the arrow *y*. 70

Similar characters of reference are employed in all of the above described views, to indicate corresponding parts:—

The can opener comprises a main bar 1, usually termed the radius-bar, which is provided at one end with a suitable handle, as 2, and may be suitably provided or formed upon its other end with a perforating device or spur, as 3, adapted to act as a center around which the cutter or blade, movably 80 or slidably disposed upon the radius-bar 1, moves when cutting. 75

As shown in the several figures of the drawings, the radius-bar is usually a flat piece of metal preferably of rectangular 85 configuration, as shown more particularly in Figs. 5 and 6 of the drawings.

Suitably disposed upon this radius-bar is the cutter or blade, the same in the present case being made from wire which is bent at 90 its one end into a suitably formed loop-shaped member as 4 adapted to be disposed upon the lower surface of the said radius-bar 1. The said loop-shaped member terminates in a laterally extending member 5, and 95 a portion 6 which extends upwardly along the longitudinal extending edge-surface 7 of the radius-bar 1. The portion 6 has connected therewith a curved or arc-shaped member 8 which extends laterally upon the 100 upper surface of the said radius-bar 1 and extends, in the same plane, as at 9, along the edge-surface 7 and then downwardly, as at 10, along said side-edge 7. The portion 10 terminates in a right-angled member 11 105 which extends over and is slidably disposed upon the lower surface portion or face of the radius member 1, and then terminates in

2

an upwardly extending member, as 12, similar to the member 10, thereby providing a U-shaped portion which closely hugs the side-edges 7 and 13, as well as the lower face 5 of the radius-bar 1. Connected with the upper portion of the said member 12, and extending along the side-edge 13 of the cutter-bar is a member 14, which terminates in a curved or arc-shaped element, as 15, extending laterally above and over the upper 10 surface of the cutter-bar 1. This element 15 terminates at 16 in a portion 17 which extends down the side 13 of the said cutter-bar, closely hugging the said side 13 and 15 then projecting into and through the said 15 loop-shaped element 4, for a distance below the lower surface of the said cutter-bar, and at that point terminating in a suitable piercing member or cutter, as 18.

20 As, has been stated, the cutter or blade-device is preferably made from spring-wire, and the tendency of the two arc-shaped members 8 and 15 is such, that the various portions 6 and 16, and 10 and 12, are caused 25 to closely hug the opposite edge-surface 17 and 13 of the radius-bar, so that sufficient frictional engagement is produced between the main cutter-member or device and the said radius-bar to properly retain the cutter 30 or blade in its adjusted position upon this radius-bar against lateral movement, and thereby provide the proper circular cutting of the top of the can or package, as will be clearly evident. The frictional engagement 35 of the said cutter-element with the various surface-portions of the radius-bar is such, however, that the movement of the cutter-element upon said bar in either direction of the arrows x or y for adjustment by the 40 manipulator, is not interfered with.

From the foregoing description of the present invention, it will be clearly evident, that a can opener has been produced which embodies simplicity in its construction, is efficient in its operation, and is most economical in its cost of manufacture.

I am aware that the essential and characteristic features of the present invention are susceptible to modification, and, therefore, I do not limit myself to the exact de- 50

tails of the construction of the device and parts as herein shown and described in the accompanying specification.

I claim:—

1. A can-opener comprising a radius-bar, 55 and a cutter element movably disposed upon said bar, said cutter-element being made of spring-wire formed with end-portions embracing the side-edges and lower surface of said bar, and arc-shaped retaining elements 60 intermediate of the end-portions of said cutter-element, said arc-shaped elements extending over the upper surface of the said radius-bar to provide frictional contact between the said cutter-element and the radius- 65 bar.

2. In a can-opener, a flat radius-bar provided at one end with a piercing point, and a cutter-element mounted upon said bar, said cutter-element being made of wire formed 70 with end-portions embracing the side-edges and lower surface of said bar, one of said end-portions terminating in a laterally extending loop-shaped end-member, and a cutter-blade extending downwardly into and 75 through the said loop-shaped end-member.

3. In a can-opener, a flat radius-bar provided at one end with a piercing point, and a cutter-element mounted upon said bar, said cutter-element being made of wire formed 80 with end-portions embracing the side-edges and lower surface of said bar, one of said end-portions terminating in a laterally extending loop-shaped end-member, and a cutter-blade extending downwardly into and 85 through the said loop-shaped end-member, and arc-shaped retaining elements intermediate of the said end-portions of the cutter-element, said arc-shaped elements extending laterally from the opposite side- 90 edges and over the upper surface of the said cutter-bar.

In testimony that I claim the invention set forth above I have hereunto set my hand this 18th day of October, 1916.

WILLIAM A. WILLIAMSON.
